UNITED STATES PATENT OFFICE.

JOHN A. SKOGERSON, OF SIOUX CITY, IOWA.

LATCH.

Application filed July 1, 1924. Serial No. 723,470.

To all whom it may concern:

Be it known that I, JOHN A. SKOGERSON, a citizen of the United States, and a resident of Sioux City, in the county of Woodbury 5 and State of Iowa, have invented certain new and useful Improvements in Latches, of which the following is a specification.

My invention relates to latches, particularly of the type used in retaining the doors 10 of vehicles in closed position, and it is my object to provide such a latch which is of simple, durable and inexpensive construction. I aim to provide in such a latch a construction wherein the movement of the 15 bolt to operative position will serve to draw the door into closer and more snug fit with the door casing, this object being preferably carried out by the use of a pivoted bolt adapted to swing into engagement with a 20 keeper having a slot with an inclined edge wherewith the bolt coacts.

Another object is to provide such a latch wherein the bolt is normally urged to operative 25 position by a spring, is retained in inoperative position when the door is opened by a swinging latch, the latch contacting with the edge of the keeper when the door is closed and thereby releasing the bolt to allow it to swing to operative position, and 30 a door knob or handle being provided which serves to retract the bolt and to open the door, the bolt-retaining latch being automatically urged into engagement with the bolt when the door is opened.

35 A still further object is to arrange the spring in such relation with the bolt and the linking mechanism connecting the bolt with the manually-operated handle, that the tension of the spring is, in effect, applied 40 to the bolt on both sides of its pivot point in order to increase the effective force of the spring as applied to the bolt.

With these and other objects in view, my 45 invention consists in the construction, arrangement and combination of the various parts of my device, whereby the objects contemplated are attained, as hereinafter more fully set forth, pointed out in my claims and 50 illustrated in the accompanying drawings, in which:

Fig. 1 is an inverted horizontal sectional view through a door and a portion of its adjacent casing, with my latch installed therein.

55 Fig. 2 is a vertical sectional view of the same taken on the line 2—2 of Fig. 1, the

door being in slightly open position, the latch being shown in inoperative position in full lines and in operative position in dotted lines. 60

Fig. 3 is an end elevation of a portion of the door, illustrating the latch from the front.

Fig. 4 is an edge elevation of the corresponding portion of the casing with the 65 keeper attached thereto.

Fig. 5 is a detail sectional view showing the bolt-retaining latch from the interior of the casing, taken on the line 5—5 of Fig. 2.

Fig. 6 is a detail sectional view of the 70 same, taken on the line 6—6 of Fig. 2.

In the accompanying drawings I have used the reference numeral, 10, to indicate generally a door casing, and 11, the door. 75 Mounted in the door in the ordinary manner is the latch casing, 12, having the front plate, 13. Fastened to the door casing, 10, and registering with the front plate, 13, is the keeper, 14, in which is the slot, 15, having an inclined edge, 16. The edge, 16, is 80 inclined downwardly in the direction of the closing motion of the door.

The bolt, 17, is pivoted on a pin, 18, and extends through a slot, 19, in the plate, 13, when in its operative position. It will be 85 seen that in moving from inoperative to operative position the bolt enters the slot, 15, and moves downwardly, engaging the inclined edge, 16, so as to draw the door laterally with respect to its casing, and thereby 90 provide a snug fit between the door and the casing bead, or the like, 19.

In order to maintain the bolt, 17, in correct position against the side of the casing, 12, the collar or washer, 20, is provided. 95

Rotatably mounted in openings in the side of the casing, 12, is the sleeve, 21, having a square opening through which is received the shaft, 22, of the actuating handle or door knob, 23. On the inner end of the shaft, 22, is removably mounted in the ordinary manner the handle, 24, by means of which the door may be opened from the inside.

Formed on the sleeve, 21, is the arm, 25, 105 which is connected by means of a link, 26, to the bolt, 17, between the pivot, 18, and the end of the bolt. A spring, 27, connects the other end of the bolt to the link, 26, at a point near its pivotal connection to the arm, 25, and the parts are so arranged that the spring tends to exert a downward push 110

against the bolt through the medium of the link, 26, and a corresponding upward pull to the end of the bolt on the other side of the fulcrum, which is added to the downward push so as to give a maximum leverage in the force tending to move the bolt to operative position.

When the door is open the bolt is maintained in inoperative position by the following described mechanism. The end of the bolt, 17, is provided with a finger, 28, which, when the bolt has been drawn to inoperative position, may be engaged by the pivoted latch member, 29. The latch, 29, as shown in Fig. 5, consists of a short bar of metal, pivoted at 30, to the front plate, 13, and extending downwardly in the path of movement of the finger, 28. The latch, 29, is normally urged into such position by means of a spring, 31, which contacts with the lug, 32. The lug, 32, extends forwardly through the slot, 33, in the plate, 13, to a position where its path of travel during the swinging shut of the door will be intercepted by the edge of the keeper, 14. The keeper, 14, may be cut away, as at 34, in order to receive the lug, 32, and a registering groove, 35, may be cut for this purpose in the edge of the casing, 10.

It will now be seen that as the door moves to closed position the lug, 32, will be engaged by the edge of the keeper, 14, and will swing the latch, 29, laterally until the bolt, 17, is released. When the bolt, 17, is released, the door and casing will be in proper register with each other in order that the bolt may enter the slot, 15.

My device is particularly adapted for use where it is desired to slam the door shut, in that the action of the spring, 27, is very rapid, and the bolt, 17, will be snapped down with such force and momentum as to seat itself deeply in the groove, 15, and to thereby secure the door in a very snug fit within the casing.

In the application of the latch to a vehicle, it will be seen that the vibration of the door caused by the travel of the vehicle will tend to seat the bolt, 17, deeper in the slot, 15, and to thereby reduce the vibration to a minimum.

When it is desired to open the door, the handle, 23, is rotated in the direction indicated by the arrow, 36, whereby the bolt will be drawn upwardly to position where the door may be opened. As soon as the door has been withdrawn from the casing, the spring, 31, will snap the latch, 29, back into position in front of the finger, 28.

My latch is very simple in construction, and there are no parts to get out of order.

Some changes may be made in the construction and arrangement of the parts of my invention without departing from the real spirit and purpose of my invention, and

it is my intention to cover by my claims any modified forms of structure or use of mechanical equivalents which may be reasonably included within their scope.

I claim as my invention:

1. In combination with a door and a door casing, a bolt pivoted in the door intermediate of its length adapted to move from inoperative position where it is contained entirely within the door, to operative position where it extends into the casing, a latch adapted to engage the bolt and to maintain it in inoperative position, said latch having a portion disposed so as to engage the casing when the door is moved to closed position and to withdraw the latch from engagement with the bolt, manually operable means for returning the bolt to inoperative position, said last means including a swinging arm, and a link attached to the arm and to the bolt at a position between the outer end and the pivot thereof and means for returning the latch to engagement with the bolt when the door is moved away from the casing.

2. In combination with a door and a door casing, a bolt pivoted in the door intermediate of its length for movement in the plane of the door from inoperative to operative position where it extends within the casing when the door is closed, means tending to urge the bolt to operative position, said means including a swinging arm, a link attached to said arm and to the bolt at a position between its outer end and its pivot, and a retractile element joining said link and the inner end of the bolt, means for retaining the bolt in inoperative position when the door is open, and means for rendering said last means inoperative when the door is closed.

3. In combination with a door and a casing having a keeper, a latch housing, a bolt pivoted in the housing and adapted to move in the plane of the door from inoperative position, where it is contained within the door, to operative position where it extends into the casing when the door is closed, a swinging latch adapted to maintain the bolt in inoperative position when the door is open, said latch having a portion extending through an aperture in the outer wall of the housing, toward the keeper, adapted to engage the edge of the keeper when the door is closed and to withdraw the latch from engagement with the bolt.

4. In combination with a door and a casing, a keeper having a slot, one edge of the slot being inclined, a bolt pivoted in the door intermediate of its length for movement in the plane of the door from inoperative position, where it is contained entirely within the door, to operative position where it is received by the slot when the door is closed, means tending to urge

the bolt into operative position, said means including a swinging arm, a link attached to said arm and to the bolt at a position between its outer end and its pivot, and a retractile element joining said link at the inner end of the bolt, the inclined edge of the slot serving, in conjunction with the bolt, to urge the door to a closer fit within its casing, and manually operable means for retracting the bolt to inoperative position.

5. In a door latch, a pivoted swinging arm, a bolt pivoted intermediate its ends and having one end adapted to engage a keeper when in operative position, a link pivoted to the arm and to the bolt at a position intermediate the keeper-engaging end of the bolt and the pivot thereof, and a retractile element joining the link and the other end of the bolt.

10. In a door latch, a pivoted swinging arm, a bolt pivoted intermediate its ends and having one end adapted to engage a keeper when in operative position, a link

pivoted to the arm and to the bolt at a position intermediate the keeper-engaging end of 25 the bolt and the pivot thereof, a retractile element joining the link and the other end of the bolt, and manually operable means for oscillating the swinging arm.

15. In a device of the class described, in combination with a door and its casing, a housing, a keeper, a bolt pivoted in the housing to swing in the plane of the door to position to engage the keeper when the door is closed, a latch pivoted to swing 30 across the path of the bolt, said latch having a lug projecting in the plane of the door toward the door casing, adapted to engage the edge of the keeper when the door is closed, and to move the latch away from 35 the path of the bolt.

20. Signed at Sioux City, in the county of Woodbury and State of Iowa, this 24th day of June, 1924.

JOHN A. SKOGERSON.
